UNITED STATES PATENT OFFICE.

CHARLES C. WIENTGE, OF PROVIDENCE, RHODE ISLAND, ASSIGNOR TO THE
HOWARD STERLING COMPANY, OF SAME PLACE.

DESIGN FOR THE BACK OF A BRUSH OR SIMILAR ARTICLE.

SPECIFICATION forming part of Design No. 21,847, dated September 6, 1892.

Application filed August 9, 1892. Serial No. 442,620. Term of patent 7 years.

To all whom it may concern:

Be it known that I, CHARLES C. WIENTGE, of the city of Providence, in the county of Providence and State of Rhode Island, have 5 invented and produced a new and original Design for the Back of a Brush or Similar Toilet Article, of which the following is a specification, reference being had to the accompanying drawing, forming part thereof.

10 The drawing represents the back of a brush or similar toilet article, illustrating my new design.

The leading features of my design for the back of a brush or similar toilet article consist in the symmetrical outline forming the handle gradually contracting to form the neck thereof and then boldly expanding to form the main portion of the back, and finally contracting to form the rounded upper end, together with the surface ornamentation consisting of a conventionalized shell-like ornament on the lower end of the handle portion, beadings extending practically parallel with the outline of the handle and connecting said 25 ornament with a somewhat similar one located at the junction of the handle with the main portion and slightly more extended in its irregular scrolls, and bold baroque-like elongated scrolls forming an irregular border 30 around the main back, leaving the central portion plain.

2 in the drawing designates the back of a brush or similar toilet article, and 3 is the handle of the same. The outline of the handle curves outward to 4 4, then gradually inward to 5 5, now boldly outward to 6 6, and then curves inward to form the rounded end of the back 2. The conventionalized shell-like ornament 7 is located at the lower end of the handle 3 and is connected by the beadings 8 8 with the ornament 9, located at the junction of the neck and handle. This ornament 9 is somewhat similar in character to that marked 7, but is more extended and displayed in its design. Extending around the back 2 45 and forming an irregular border on the plain surface thereof are the elongated more or less shell-like scrolls 10, 11, 12, 13, and 14, from which extend at intervals slight foliations.

What I claim is—

The design for the back of a brush or similar toilet article, as herein shown and described.

In witness whereof I have hereunto set my 55 hand.

CHARLES C. WIENTGE.
